W. T. BENHAM,
DIAL AND DIAL RIM OF COMBINATION LOCKS.
APPLICATION FILED JAN. 28, 1913.

UNITED STATES PATENT OFFICE.

WILLIAM T. BENHAM, OF RISING SUN, INDIANA.

DIAL AND DIAL-RIM OF COMBINATION-LOCKS.

1,113,866.

Specification of Letters Patent. Patented Oct. 13, 1914.

Application filed January 28, 1913. Serial No. 744,607.

To all whom it may concern:

Be it known that I, WILLIAM T. BENHAM, a citizen of the United States, residing at Rising Sun, in the county of Ohio and State 5 of Indiana, have invented new and useful Improvements in Dials and Dial-Rims of Combination-Locks, of which the following is a specification.

My improvements relate to dials for combination locks, such as are ordinarily used 10 on safes, file cases and the like.

My improvements will render the running of a combination, no matter how intricate, so simple that combination locks can be 15 conveniently used not only on all places where heretofore found practical, but on doors of residences, stables, garages, factories and the like, where such locks would be far safer than any common lock.

20 My improvements may be attached to any combination lock dial now in use, and consist fundamentally of a notched dial rim ordinarily placed for convenience outside of the numbered dial rim with a notch on 25 the same radius as each of the numbers or notches on the dial; and a lever fixed to the dial and having a point, wheel or the like adapted to fit into each of the notches of the notched rim.

30 For greater accuracy and rapidity in operation, separate means of detecting groups of units on the dial, as fives or tens, may be provided. One means of accomplishing this is by placing holes at any convenient distance from center around the dial, and a 35 pin on the dial lever, adapted to enter these holes in passing, when desired.

The object of the invention is to permit 40 the running of a combination without reliance upon the sight, and if the device on the lever adapted to enter the notches of the notched rim, is a small raw-hide roller or the like, no sound need be made in running the combination, and entire reliance 45 can be placed upon the sense of touch. Obviously, if a hard metallic point was provided instead of the roller, this would cause a clicking sound when it entered each notch, so that entire reliance could be placed upon 50 the sense of hearing, and if the usual figures are on the dial, the combination could be run by sight, as usual, so that any one, two or all of the senses of sight, hearing and touch can be relied upon where my improvement 55 is applied to a numbered combination lock dial. My chief purpose, however, is to

rely upon the sense of touch only, as then no sound will be made, and it will be impossible for any person to learn the combination by listening to another run it. In 60 fact, with my improvement, numbers on the dial would be unnecessary, or even the usual numbered gradations, and the combination could be run by anyone who knew it, in the dark as well as in the light, and by persons 65 of defective sight.

The dials may be numbered and notched in the usual way, to the right only, but the greatest convenience and accuracy will be attained by numbering the dial both ways 70 from zero, as disclosed in my application for Letters Patent in numbering the graduations of lock dials, Serial Number 744,606, filed January 28, 1913.

My invention is illustrated in the accompanying drawings, in which—

Figure 1 is a front elevation of a safe dial, numbered in both directions from a starting point, zero, from one to twenty five, inclusive, and shows my improvements 80 adapted thereto; Fig. 2 is a vertical axial section through the dial and its attached notched rim and peripheral flange graduated with holes, and with the lever and its attachment in position, partly in section to 85 show construction. The dial arbor is shown broken away. Fig. 3 is a detail of an alternative form of rolling point to take the place of the roller or wheel.

Referring now to the drawings, A is the 90 rotatable dial with knob a, and its neck a¹, and the peripheral gage a², with a mark a³, for each unit of measure, and numbers, 5, 10, 15, 20, 25 each way from the starting point which indicate groups of 5 units each, in the 95 usual way. The dial armor a⁴ is adapted to receive the tumblers (not shown) in the usual way.

A rim B around the dial proper A has a mark b to indicate to the sight the point 100 from which rotation is started, and an annular boss b¹ is provided with the notch b² to indicate to the touch or hearing or both, the point from which rotation is started, and other notches b³, from 1 to 25 inclusive, both 105 to the right and the left, each on a radius with one of the marks a³ of the dial A when the dial is set for beginning operation.

The rim B has a flange b⁴ with holes b⁵ each on a radius with one of the numbers of 110 the dial 5, 10, etc., when the dial is set for beginning operation.

A lever C with fork c at its inner end seating astride the neck a¹ of the dial knob, is loosely pierced and held in position to secure rotation of the dial A by a stud a⁵, capped by head a⁶ which limits the outward movement of the lever. A spring c¹ fixed to the lever C seats against the under side of the dial knob a and keeps the lever normally depressed so that the roller W (hereinafter described) is in contact with notches in the annular boss b¹. Underneath the lever C, in line with the notched annular boss b¹ is a roller W, journaled in a bracket c² fixed to the lever C.

The lever is rotated by grasping a handle D which is fixed to a pin d. This pin has a sliding fit in the lever C, its outward movement is limited by the collar d¹, so as to keep the inner end of the pin just clear of the flange b⁴ and out of the holes b⁵, and the pin is held in this position by the spring d² until pressure inward is applied to the handle D.

The use of the holes b⁵ and pin d will be seen in a combination involving high numbers;—for example, 21. After starting from center, the operator would press inward on the handle D until the pin d had come to the fourth hole b⁵ being the one at 20. The count would be four holes and 1 notch, instead of 21 notches. When the pin is not to be used, the handle is pressed sidewise, not inward, to rotate the dial either to the right or the left, and the jumping of the lever as the roller passes into each of the notches readily enables the one running the combination to count the notches by the sense of touch.

Instead of the roller W, a ball E rotatably mounted in a socket e fixed to the lever C, and held down to position by a bearing e¹, may be used. With a properly shaped notch this would make such a rolling contact as to make little sound.

I claim as my invention and desire to secure by Letters Patent of the United States,

1. A dial for combination locks, having a fixed member and a rotatable member, a notched gage on said fixed member, a lever on said rotatable member whose free end overlaps the notched gage, a roller on said lever adapted to contact with the notched gage and a spring adapted to press said roller against the notched gage.

2. In combination locks, the combination of a fixed dial rim with notches graduated therein, and holes therein indicating groups of these graduation units, and a dial adapted

to rotate within said rim, having graduations and groups of its units of graduation corresponding to those on the rim, a lever fixed to the dial and adapted to overlap the rim, and a pin through the lever adapted to seat in the holes in the rim.

3. A dial for combination locks, having a fixed member and a rotatable member, a notched gage on said fixed member, a gage formed by a series of holes in said fixed member, a lever on the rotatable member whose free end overlaps the gages on said fixed member, a roller on said lever adapted to contact with the notched gage, a spring adapted to press said roller against the notched gage, a pin through said lever adapted to enter said holes in the fixed member and a spring adapted to normally hold said pin free of said holes.

4. In combination locks, the combination of a rotatable dial, and a fixed dial rim, the dial being graduated and the rim having notches on radii of the said graduations, and a lever adapted to be used in rotating said dial, and to overlap said notched rim, and a rotating point on said lever adapted to seat in said notches.

5. In combination locks, the combination of a fixed dial rim with notches graduated therein, and holes therein indicating groups of these graduation units, and a dial adapted to rotate within said rim, having graduations and groups of its units of graduation corresponding to those on the rim, a lever fixed to the dial and adapted to overlap the rim, a roller on the lever adapted to seat in the notches of the rim and a pin through the lever adapted to seat in the holes in the rim.

6. In combination locks, the combination of a rotatable dial and a fixed dial rim, a notched gage on said rim, a gage formed by a series of holes in said rim, a lever adapted to rotate said dial whose free end overlaps the gages on the rim, a roller on said lever adapted to seat in the notches of the rim, a spring adapted to press said roller against the notched gage, a pin loosely piercing said lever adapted to enter the holes in the rim and a spring adapted to normally hold said pin free of said holes.

In testimony whereof I have hereunto set my hand in presence of two subscribing witnesses.

WILLIAM T. BENHAM.
